MUSICAL TUNING DEVICE

William D. Gladstone, New York, N. Y., assignor
to The Fred. Gretsch Manufacturing Co.,
Brooklyn, N. Y., a corporation of New York

Application February 23, 1937, Serial No. 126,971

3 Claims. (Cl. 84—411)

My invention relates to devices for tuning percussion musical instruments and especially to the tuning of the drums.

The principal object of my invention is to provide means whereby the diaphragms of a drum may be controlled independently and may also be controlled in unison, by means of a single key movement which will affect the degree of tautness of the diaphragm which is so essential in obtaining the proper tone and resonance of the two diaphragms of a drum.

Another object of the particular forms of my device is to dispense with unusual projections beyond either end of the drum. The angular ends of the adjusting rods, by means of which they can be rotated, are situated below the top of the batter head counter hoop.

Other objects of my invention will appear during the course of the detailed specification referring to the accompanying drawings wherein:

Figure 1 is a front view of one of the tuning devices of my invention shown attached to a drum.

Figure 2 is a section through the line 2—2 of Figure 1.

Figure 3 is a plan view of Figure 1.

Figure 4 is a vertical section through a key adapted to operate with the devices of my invention.

Figure 5 is a view partly in section of the two drum head adjusting rods, taken apart.

Figure 6 is a front view of a modified form of the device of my invention, shown attached to a drum.

Figure 7 is a section through the line 7—7 of Figure 6.

In the particular form of a device of my invention shown in Figures 1, 2, 3, 4 and 5, A represents the drum which is provided with the usual shell 10, counter hoop 11, at the batter head end of the drum. The batter head diaphragm 12 of the drum passes over the inwardly bent portion 13 of the side 10, thence downwardly and around the flesh hoop 14 and the counter hoop 11, abutting upon the flesh hoop 14 and being vertically movable along the side 10 of the drum; 15 is a tubular supporting member having lugs or legs 16 which are rigidly secured to the side 10 of the drum in any conventional manner, for instance, by means of screws 17—17. The tubular member 15 is provided interiorly with left and right hand threadings, and within this supporting member is a tubular member 18, the upper smooth and preferably round end of which terminates in a key-receiving member 19. The

free end of the member 18 is exteriorly threaded to thread with the threaded interior bore of the supporting member 15. The tubular member 18 passes also through a bore of the counter hoop 11 at the batter head end of the drum, abutting 5 with its key receiving member 19 against the bore, thereby holding the counter hoop and thus the batter head end in any adjusting position.

It will thus be seen that if the angular recess 20 of the key shown in Figure 4 be placed over 10 the element 19 of the tubular member 18, and be revolved in one direction, the tubular member 18 will move downwardly, carrying along the counter hoop 11, thus tightening the batter head diaphragm 12, and that a reverse movement of 15 the key will loosen the batter head diaphragm 12.

Also, threaded within the free end of the supporting member 15 and vertically movable therein, is a second threaded member 21. This member 21 is passed through a bore of the counter 20 hoop 11' of the snare head and carries a fixed collar 22 at its outer end, the collar abutting upon the bore of the snare end of the drum. The snare head diaphragm 12' of the drum passes over the inwardly bent portion 13' of the side 25 of the drum, thence downwardly and around the flesh hoop 14', abutting upon the hoop 11' and being vertically movable along the side 10 of the drum.

The member 21 extends beyond its threaded 30 portion and terminates in a short reduced end 23 of angular cross section, over which a tubular member 24 of angular interior configuration is placed fixed in any suitable manner to the shoulder forming the reduced end 23 of member 21, 35 and adapted to receive a control means to be described hereinafter.

Loosely extending within the tubular member 18 controlling the batter head diaphragm 12, and passing through the hollow key member 19, 40 to form a key member 25 is a rod 26 having its stem of preferably angular configuration extended down into the member 24 of the snare head controlling member 21, to operatively engage therewith. 45

It is evident that a revolution of the rod 26 will tighten, or loosen, the snare head diaphragm 12' dependent upon the direction of the revolution.

The key shown in Figure 4 has three operating 50 recesses, recess 20 being formed to fit the member 19 for tightening the batter head diaphragm 12, the recess 27 for the snare head diaphragm 12' and the recess 28 in the central stem of the key is so formed that the outer enlarged portion 55

will fit the element 19 and the inner reduced portion will fit the element 25, and hence, it is evident that when this master portion 28 of the key is employed it will revolve both the tubular member 12 and the member 26, thus simultaneously tightening or loosening both the batter head diaphragm and the snare head diaphragm, it being noted that the threads in the supporting member 15 relative to the members 18 and 26 are left hand threads 50 and right hand threads 51 respectively.

The simplicity and ease of its removal from and attachment to a drum are evident when it is considered that the device can be disassembled by simply revolving the member 18 from its threaded attachment, and withdrawing it from the member 15, and then from its attachment from the counter hoop 11 of the batter head. The same holds good with reference to the removal from, or attachment to the snare head operating member 21.

The usual method for operating the device consists in alternately tightening the diaphragms 12, 12', by the employment of the ends 25 of the key shown in Figure 4 until the desired resonance or tone is obtained. This condition is maintained until, because of atmospheric conditions, or otherwise, the diaphragms have become unduly loosened or tightened in which event 30 both diaphragms are simultaneously and uniformly tightened, or loosened, by the employment of the key end 28 as above described to produce the original desired resonance or tune, all of which operations are performed at the 35 batter head portions of the drum, thus avoiding the necessity of reversing the drum.

In the modified form of my invention illustrated in Figures 6 and 7, there is shown a device of the same general type as that illustrated in Figures 1 to 5 inclusive.

This particular form of device of my invention consists of a supporting member 30, having the two extended lugs 31-31, which are fixedly attached to the side 32 of a drum A by means 45 of the screws 33-33.

That portion of the device adapted for tightening, or loosening the batter head diaphragm is exactly of the same construction as shown and described with reference to Figures 1 to 5, and 50 it is believed that a brief mentioning of the batter head tightening member will suffice to make the construction of this modification clear.

That portion of the device adapted for tightening, or loosening, the batter head diaphragm 55 34 consists of a hollow rod 35, the upper end of which carries the key receiving member 36, while the lower end 37 of the rod being externally threaded to thread with the threaded bore 38 of the supporting member 30. The rod passes also 60 through an opening 39 of the batter head tightening means, abutting with its key receiving member 36 upon the opening 39.

It is evident that a revolution of the rod 35 will tighten, or loosen, the batter head diaphragm 34, dependent upon the direction of revolution.

The elements of construction adapted for tightening, or loosening, the snare head diaphragm consists of a rod 40, the upper end of 70 which terminates in an extended reduced angular portion 41, the rod carrying a fixed collar 42 and having an intermediate threaded portion 43. The rod 40 passes through the opening 44 in the counter hoop 45 of the snare head, abutting 75 with its collar 42 upon the bore. It also

passes through the threaded opening of the supporting member 39, the reduced angular portion 52 of the member 40 extending into the tubular member 41 of angular interior configuration loosely positioned within the tubular member 35. A key receiving member 47 passes through an opening in the key receiving member 36 and is maintained from vertical movement as shown. The key receiving member extends downwardly into the tubular member 35 and into the reduced angular member 46 which is positioned within the tubular member 41.

The mode of operation of this modified form is accomplished substantially the same way by 15 means of the key illustrated in Figure 4, as has been described with the preferred embodiment shown in Figures 1 to 5.

I do not limit myself to the particular size, shape, number, arrangement or material of 20 parts as shown and described, as these are given simply as a means for clearly explaining my invention.

What I claim is:

1. In a drum tuning device, in combination, a 25 supporting member fixedly attachable to the side of a drum, a tubular adjusting rod detachably engageable with a counter hoop of a drum, said rod having threaded adjusting engagement with said supporting member, an end portion of said 30 tubular rod being accessible beyond and adjacent the point of engagement of said rod with the counter hoop by means of which the rod can be individually rotated, a second adjusting rod detachably engageable with the other counter hoop 35 of a drum and having threaded adjusting engagement with said supporting member, said second adjusting rod the end portion of which is within said supporting member is of reduced angular cross-section, a cooperative member 40 loosely positioned within the first named revolvable adjusting rod having its inner end extended to be received in firm engagement with the angular extension of the second adjusting rod, an end portion of said cooperative member accessible 45 from the outer end extending beyond and adjacent to, the end portion of said tubular rod, by means of which said second adjusting rod is individually rotated, and coupling means discon-nectively engageable concomitantly with the outer 50 end portion of said tubular rod and with the end portion of said rod member positioned within said tubular rod and forming a cooperative part of said second adjusting rod, and being thus adapted for simultaneously rotating both of said 55 adjusting rods together as a unit.

2. In a drum tuning device, in combination, a supporting member fixedly attachable to the side of a drum, a tubular adjusting rod detachably engageable with a counter hoop of a drum, said 60 rod having threaded adjusting engagement with said supporting member, an end portion of said tubular rod being accessible beyond and adjacent the point of engagement of said rod with the counter hoop by means of which the rod can be 65 individually rotated, a second adjusting rod detachably engageable with the other counter hoop of a drum and having threaded adjusting engagement with said supporting member, said second adjusting rod having its free end ter- 70 minating into an angular shaped extension, a cooperative tubular member loosely positioned within the first named revolvable adjusting rod and having its short tubular inner end adapted to firmly receive the said angular extension of 75

the second adjusting rod, an end portion of said cooperating rod accessible from the outer end extending beyond, and adjacent to the end portion of said first named tubular adjusting rod, by means of which said second adjusting rod is individually rotated.

3. In a drum tuning device, in combination, a supporting member fixedly attachable to the side of a drum, a tubular adjusting rod detachably engageable with a counter hoop of a drum, said rod having threaded adjusting engagement with said supporting member, an end portion of said tubular rod being accessible beyond and adjacent the point of engagement of said rod with the counter hoop by means of which the rod can be individually rotated, a second adjusting rod detachably engageable with the other counter hoop of a drum and having threaded adjusting engagement with said supporting member, said second adjusting rod having its free end terminating

into an angular shaped extension, a cooperative tubular member loosely positioned within the first named revoluble adjusting rod and having its short tubular inner end adapted to firmly receive the said angular extension of the second adjusting rod, an end portion of said cooperating rod accessible from the outer end extending beyond, and adjacent to the end portion of said first named tubular adjusting rod, by means of which said second adjusting rod is individually rotated, and coupling means disconnettively engageable concomitantly with the outer end portion of said tubular rod and with the end portion of said rod member positioned within said tubular rod and forming a cooperative part of said second adjusting rod, and being thus adapted for simultaneously rotating both of said adjusting rods together as a unit.
